Primary Examiner—Ian Simmons*Assistant Examiner*—Mark A Goodwin(74) *Attorney, Agent, or Firm*—Wood, Herron & Evans, LLP(57) **CLAIM**

The ornamental design for the subterranean emergency shelter, as shown and described.

DESCRIPTION

FIG. 1 is a perspective view of a subterranean emergency shelter showing my new design;

FIG. 2 is a front elevation view thereof;

FIG. 3 is a rear elevation view thereof;

FIG. 4 is a right side elevation view, the left side elevation view being a mirror image thereof;

FIG. 5 is a top plan view thereof; and,

FIG. 6 is a bottom plan view thereof.

The broken lines in the figures of the subterranean emergency shelter are for illustrative purposes only and form no part of the claimed design.
